UNITED STATES PATENT OFFICE

HOLMAN HARRY LINN, OF MORRIS, NEW YORK, ASSIGNOR TO THE LINN MANUFACTURING CORPORATION, OF MORRIS, NEW YORK, A CORPORATION OF NEW YORK

TRACTOR

Original application filed May 13, 1924, Serial No. 713,022. Divided and this application filed August 27, 1928. Serial No. 302,365.

This case is a division of application Ser. No. 713,022, filed May 13, 1924, and relates more particularly to the compensating device which contributes to the flexibility of the track by permitting it to take up freely on uneven surfaces.

The nature of the invention consists in the support and carriage of the idler sprockets by compensating devices of special construction and arrangement of parts for the purpose and with the result of maintaining proper track tension for any surface; of automatically taking up wear; and of providing for minimum breakage of sprockets, due to trapping of obstructions, by permitting the sprockets to slip one tooth and thus insure ejection of the obstruction, stones, mud, snow, ice, or whatever it may be.

The invention, in its preferred form, is illustrated in the accompanying drawings, forming a part hereof, wherein

Figure 1 is a plan view of the compensating or slide frames, showing their general arrangement with respect to the main and auxiliary frames.

Fig. 2 is a side elevation of one of the track units.

Fig. 3 is a plan view of the slide frame casting.

Fig. 4 is a side view of the same.

Fig. 5 is a section on line 5—5 of Fig. 3.

Fig. 6 is a front edge view, partly in section.

According to the invention, the main frame, consisting of longitudinally ranging members 5, is provided with an auxiliary frame consisting of side bars 6 secured in spaced parallel relation to the main frame members by cross bars 7. Hangers 8, secured to the

auxiliary and main frame elements, accommodate a transverse shaft 9, the ends of which form pivotal or trunnion mountings for load transferring elements or rocker beams 10.

The latter are supported fore and aft by pairs of relatively adjustable runner blocks 11. The details of the runner blocks are set forth in the parent application.

A roller chain 12 is adapted and arranged to travel over the runner blocks to eliminate friction between them and articulated tracks

13. The latter are suspended on sets of double or twin sprockets 14 and 15 whereof one is a driving sprocket and the other an idler sprocket. It is with the support and carriage of the idler sprocket, providing for its complete responsiveness to changing conditions of stress on the track, that the present case is particularly addressed. Generally speaking the idler sprockets are mounted in compensating slide frames, yieldable under spring control to permit the idler sprockets to vary the tension of the articulated or flexible tracks in accordance with varying ground surface conditions.

In order to insure adequate strength and ruggedness to meet the severe service imposed upon them, the slide frames preferably are of unit or integral construction of generally hair pin form, consisting of side sills 16 joined at one end by a yoke 17 and a bolster for the latter consisting of a straight transverse member 18.

The side sills or frame members 16 have continuous grooves or channels 19 and through slots or openings 20. The channels 19 receive the lower flanges of the main and auxiliary frame members 5 and 6, respectively. The through slots or openings insure proper heat treatment.

Cast integral with the side sills are journals 21 for the shaft or trunnion element of the idler sprocket, the journals having reinforcing webs 22.

The yoke 17 is formed with an opening 23 for the reception of a headed rod 24 which extends loosely through a thrust block or element 25 rigidly secured between the main and auxiliary frame members. Between the thrust block and the extremity of the rod 24 there is a heavy coil spring 26, which may be adjusted, as required, through the medium of nuts 27 and 28. Evidently the slide frames and the idler sprockets are held in normal position by the springs 26, but are capable of overcoming the resistance of the springs to provide the necessary compensating adjustment to relieve strain on the tracks.

As set forth in the parent application, the tracks are self-clearing in the event of "building up" conditions, namely, when rocks, ice,

wet snow or other substances are trapped between the sprockets and tracks. Such conditions are overcome by the responsive action of the compensating slide which permits the sprockets to slip to forcibly eject the trapped material. Moreover, the instant responsiveness of the slide to permit slippage of the tracks will minimize breakage due to conditions brought about through carelessness or ignorance of a "green" driver, as, for example, in bad going and in low gear when he "steps on it".

Having described my invention, I claim:

A carrier for tractor frames, including a hair-pin frame having side sills and a transverse yoke connecting them at one end, each of said sills being formed with longitudinally ranging channels to permit sliding co-operation of the carrier in the tractor frame, and idler-sprocket shaft bearings carried by the sills intermediate their ends and below said channels.

In testimony whereof I affix my signature.

HOLMAN HARRY LINN.
